DESIGN FOR A BELT FOR PERSONAL WEAR

Morris Sachs, Rochester, N. Y., assignor to
Hickok Manufacturing Company, Inc., Rochester, N. Y., a corporation of New York

Application November 12, 1934, Serial No. 53,980

Term of patent 3½ years

To all whom it may concern:

Be it known that I, Morris Sachs, a citizen of the United States, residing at Rochester, in the county of Monroe and State of New York, have invented a new, original, and ornamental Design for Belts for Personal Wear, of which the following is a specification, reference being had to the accompanying drawing, forming part thereof.

The accompanying drawing illustrates a perspective view of the belt, the outstanding feature

of which is the chain simulation, continued throughout substantially the entire length of the belt body, the shaded lines denoting contrasting colors, whereby the design is made to plainly appear.

I claim:

The ornamental design for a belt for personal wear, as shown and described.

MORRIS SACHS.
